UNITED STATES PATENT OFFICE.

WILLIAM H. V. ROSING, OF ST. LOUIS, MISSOURI.

ROOF-CARLINE.

1,098,687.

Specification of Letters Patent. Patented June 2, 1914.

Application filed November 18, 1913. Serial No. 800,746.

To all whom it may concern:

Be it known that I, WILLIAM H. V. ROSING, a citizen of the United States, and a resident of the city of St. Louis and State of Missouri, have invented certain new and useful Improvements in Roof-Carlines, of which the following is a specification.

This invention relates to a built-up metal carline having its principal members of 10 rolled or pressed section, and which embodies the necessary strength and rigidity to resist the many different stresses to which a carline is subjected.

The object of the invention is a carline 15 for a freight car roof adapted to stiffen the roof against distortion from any or all causes.

The improved carline is clearly set forth in the following description and shown in 20 the accompanying drawing, in which like numbers designate like parts, and

Figure 1 represents a plan view of the finished carline, assembled between the side plates of a car roof; Fig. 2 is a side elevation of the carline of Fig. 1, showing also the ridge pole and purlins in cross section; Fig. 3 represents an end elevation of one leg of the carline, showing the foot for securing it to the side plates; and Fig. 4 represents a transverse section through the center of a carline on the line 4—4 in Fig. 1, 30 illustrating the manner of securing the channels together by top and bottom cover plates. This figure also shows the ridge pole of the car in cross section, and a ridge pole bolt.

The carline 11 is made of two channel irons 12 connected by plates 13. Each carline thus formed is in plan X shape with 40 the diverging ends turned outwardly, and adapted to be secured to the side plates 14. Holes are suitably put in the upper flanges of the carline to secure wooden members, as roof purlins and the like. The cover plates 45 13 are riveted to the upper and lower flanges of the channels and rigidly connect the bent sections at the center.

The ridge pole 15 and purlins 16 may be secured to the carlines by bolts 17. The 50 purlins form braces for the legs of the carlines to stiffen them against twisting.

The advantages of my invention are the utilization in the carline throughout of a full section of metal in each member, without 55 cutting away any portion of the original section, or altering or reducing its strength.

By connecting the two sections by cover plates at the middle, forming a box girder at the ridge, a structure is produced of maximum strength and minimum weight. The 60 box section at the center will resist both the vertical and longitudinal strains, and especially the torsional strains produced in freight car carlines.

Having described a particular embodiment of my invention, I do not limit myself thereto, but desire to secure by Letters Patent the following:

1. In a car roof, a built-up carline consisting of main half-length members extending from the side plates to the ridge and converging at their middles, and a middle connecting member secured to the middle of each of said half-length members and having a horizontal upper face adapted to support a ridge piece, both ends of each of said half-length members sloping downward toward the same side of the car and being secured to the side plate of the car. 70

2. A carline comprising two channel bar 80 sections placed on edge and extending from the side of the car to near the ridge, and having portions bent to lie parallel to the ridge line, means for securing said parallel portions together consisting of a connecting 85 member rigidly secured thereto, and a stiffening plate secured to the lower flanges of said channel bars near the ridge.

3. A carline comprising two end members bent at the middle and each having its ends 90 in the same plane and extending in the same general direction, the middle portions of said end members being secured together by means of top and bottom plates, and the end portions extending downwardly away from 95 each other and having their extremities adapted to be secured to the side plates of a car.

4. In a car roof, a built-up carline consisting of V-shaped members placed with 100 their points adjacent to each other, and a pair of cover plates secured thereto and enclosing the space between the points of said V-shaped members, the ends of said V-shaped members diverging toward the same 105 side of the car and being secured to the side plate of the car.

5. A carline comprising a box girder middle portion and end portions diverging 110 downwardly therefrom and adapted to be secured to the side plates of a car.

6. A carline comprising a box girder

middle portion and channel-shape end portions diverging downwardly therefrom and adapted to be secured to the side plates of a car.

7. A carline comprising a horizontal middle portion and end portions diverging downwardly therefrom and adapted to be secured to the side plates of a car, said middle portion resembling a box girder in

cross-section and being arranged crosswise to of the carline.

Signed at St. Louis, Missouri, this 5th day of November, 1913.

WILLIAM H. V. ROSING.
